CONTROLLED SWEATBAND GUIDE

Isidore Reiser, New York, N. Y.

Application October 7, 1940, Serial No. 359,995

2 Claims. (Cl. 112—15)

This invention relates to sewing machines for sewing sweat bands to hats.

In present practice it is customary for the operator to turn the hat inside out before sewing in the sweat band in order to have full visibility of the sweat band and to be able to guide one edge of the band in line with the lower edge of the crown.

It has been found that this turning of the hat inside out deforms the shape of the hat and leaves permanent damage marks on the hat, unless reblocked.

An object of this invention is to provide mechanism whereby a sweat band may be stitched to the inner surface of the hat without turning the hat inside out and thus obviating the resulting damage to the hat and the necessity of reblocking.

Another object of this invention is to provide mechanism comprising a self-contained sweat band guiding and cutting off and feeding means, whereby the operator may easily sever the sweat band to its proper length and on the proper bias before completing the sweat band sewing operation.

With the above and other objects in view, the invention will be hereinafter more particularly described, and the combination and arrangement of parts will be shown in the accompanying drawing and pointed out in the claims which form part of this specification.

Reference will now be had to the drawing, wherein like numerals of reference designate corresponding parts throughout the several views, in which:

Figure 1 is a front elevation of a sewing machine having the sweat band guide mechanism applied thereto.

Figure 2 is a central longitudinal cross-sectional view of the guide mechanism.

Figure 3 is a cross-sectional view, the section being taken as on line 3—3 in Figure 2.

Figure 4 is a cross-sectional view, the section being taken as on line 4—4 in Figure 2.

In the illustrated embodiment of the invention, the numeral 10 indicates a sewing machine comprising a frame 11, a standard 12, a main shaft 13, an oscillating arm 14 pivoted at 15 and operated by a pitman 16. The lower end of the pitman is in engagement with an eccentric (not shown), on the main shaft 13.

The sewing machine comprises a reciprocating needle bar 17, a needle 18, a presser foot 19 and a bottom feed-dog. These parts operate in a

manner well known in the art, as shown in Patent No. 1,085,401.

The sewing machine has been mounted on an off-set pedestal 21, and the base 22 of the sewing machine is in overhanging relation with the pedestal. A table 23 has a vertical extension 24 carrying a pivot 25 on which a roll 26 of strip fabric 27 has been rotatably mounted.

The sweat band guide 30 comprises a hollow rear member 31 having a sideways extending arm 32 which is bolted to a vertical extension 33 of the sewing machine base 22 in a manner as to position the lengthwise side of the guide 30 substantially upright.

The rear member 31 of the guide 30 has its upper end portion 34 curved outwardly and contacting with the base 22. A lever 35 has been pivotally mounted on a pin 36 in the vertical side walls 37 of the guide 30. A coil spring 38 intermediate the lever 35 and a hollow threading member 39 presses the upper edge of the lever 35 in pressure contact with the uppermost edge of the guide 30 and serves to support a fabric strip or sweat band for movement under the presser foot 19 for feeding movements by the sewing machine.

The hollow threading member 39 has been pivotally mounted on a pin 40 in the vertical side walls 37 of the guide 30 with its upper wall in pressure contact with a toothed roller 41. The roller 41 has been rotatably mounted on a pin 42 in the vertical side walls 37 of the guide 31.

A knife 43 carried by the lever 35 is guided by lugs 44 on opposite sides thereof and in alignment with an angularly positioned slot 45 in the rear member 31.

As shown in Figure 2 the sweat band 27 has been threaded through the guide 30, in a manner which permits the operator to first press down the lever 35 and force the knife 43 into the slot 45 and severs the sweat band in bias form. The operator then rotates the toothed roller 41 and causes the lower portion of the band to be raised by the roller past the uppermost edge of the guide 30 and to be moved under the raised forward end of the presser foot for feeding movements by the well known sewing machine feed. It is to be understood that the operator actuates the lever 35 away from contact at the uppermost end portion 34 before actuating the toothed roller.

It will thus be seen that my sweat band guide 30 serves first to frictionally support the sweat band at a point adjacent the feed dog of the sewing machine and prevents overfeeding and wrinkling of the sweat band while it is sewed

inside the hat. The guide 30 also serves for severing the sweat band in a definite angular direction, and also serves for raising the cut-off lower portion of the fabric strip into position adjacent the presser foot for repeating the said operations when stitching another sweat band into another hat. As shown in Figure 1 it will be noted that the roller 41 is positioned within the threading member 39 so as to be adapted to feed the fabric in the same linear direction as the line of feed of the sewing machine.

The sewing machine 10 is of the chain stitch type wherein an article is stitched with only one thread, and wherein the upper surface of the article shows a straight line of stitches while the lower surface of the article shows chain-strokes.

As shown in Figure 1, a hat 46 has been positioned in operating relation conforming to the present invention. The hat 46 has not been turned inside out and when the sweat band has been stitched into the hat the chain stitches show only on the inner surface of the hat. The outer surface shows straight line stitches. This arrangement of the stitching is very desirable because exposed chain stitching necessitates the addition of a ribbon to cover the unsightly chain stitching.

It will thus be noted that the prior practice of turning the hats inside out prior to stitching the sweat bands is hereby obviated. With the method of operation herein disclosed it is not necessary to turn the hats inside out and there is no necessity for reblocking a hat after stitching the sweat band therein.

I have provided a bolt 47 and nut 48 for tensioning the supply roll 26. This tensioning makes it possible to control the length of the sweat band material being fed to the hat during the stitching operation. I can thus decrease the length of the sweat band fed to the respective hats and thereby vary the hat size of the hats as desired.

In accordance with the patent statutes I have described and illustrated the preferred embodiment of my invention, but it will be understood that various changes and modifications can be made therein without departing from the spirit of the invention as defined by the appended claims.

I claim:

1. In a sewing machine for sewing rolled sweat band fabric to hats, the combination of an overhanging work-supporting base and a bottom feed-dog and presser-foot, a self-contained guiding, shearing and feeding means carried by said base

with its lengthwise side in an upright position, said guiding means comprising a hollow rear member, a spring-pressed lever pivoted on said rear member and having its upper edge in pressure contact with said rear member and being adapted for frictionally supporting a fabric strip at said upper edge for feeding movements by said sewing machine, a cutting means supported within said guiding means in inclined relation therewith and to the line of feed of the strip for severing said strip in bias form, said cutting means being concealed within said guiding means, a table on which said sewing machine is mounted, said table having means for rotatably supporting a roll of said sweat band fabric below said guiding means, said guiding means having a hollow pivotally mounted threading member thereon for receiving said strip in an upward feeding direction whereby a fabric strip fed from said roll directly into a hat may be stitched to the inner surface of said hat, said base and said guiding means being of a size adapted to enter into the crown of said hat, said guide terminating at its upper end in front of said work supporting base to permit said bottom feed-dog to feed said sweat band from underneath.

2. In a sewing machine for sewing rolled sweat band fabric to hats, the combination of an overhanging work-supporting base and a presser-foot and a self-contained guiding, shearing and feeding means carried by said base, said guiding means comprising a hollow rear member, a hollow spring-pressed lever pivoted on said rear member and having its upper edge in pressure contact with said rear member and being adapted for frictionally supporting a fabric strip at said upper edge for feeding movements by said sewing machine, a cutting means supported within said guiding means, said cutting means being concealed within said guiding means, said lever being adapted to actuate said cutting means, a table on which said sewing machine is mounted, said table having means for rotatably supporting a roll of sweat band fabric below said guiding means, a hollow threading member pivotally mounted in said guide and having roller means for feeding said strip in an upward direction whereby said fabric strip may be fed from said roll directly into a hat and be stitched to the inner surface of said hat, said work-supporting base and said guiding means being of a size adapted to enter into the crown of said hat.

ISIDORE REISER.
